Specification for Design.

Patented Jan. 18, 1921.

Application filed December 8, 1919. Serial No. 343,427. Term of patent 7 years.

To all whom it may concern:

Be it known that I, MILTON C. STERN, a citizen of the United States of America, residing at Dayton, in the county of Montgomery and State of Ohio, have invented a new, original, and ornamental Design for Autographic Registers, of which the following is a specification, reference being had to the accompanying drawings, forming part thereof.

In the drawings:—

Figure 1 is a side elevation illustrating

an autographic register of my improved design; and

Figs. 2 and 3 are front and rear end elevations, respectively, illustrating an autographic register of my improved design.

I claim:—

The ornamental design for an autographic register as shown.

MILTON C. STERN.
